EARTH BORING DEVICE

Clyde E. Bannister, Akron, Ohio

Application February 17, 1934, Serial No. 711,713

16 Claims. (Cl. 255—4)

This invention relates to earth boring apparatus of the advancing motor type and its chief objects are to provide speed and to provide economy in the drilling of holes and especially large holes such as oil wells and mine shafts.

More specific objects are to provide conveniently and economically for drilling a deep hole without successive reductions of diameter such as are necessary in the case of apparatus heretofore used; to provide for conveniently and economical drilling a downward extension of a hole with a diameter equal to or greater than the diameter of the hole farther up or of a casing therein; and to provide for the progressive placing of a casing in a hole drilled by the hydraulic method without substantial interruption of the drilling operation.

The present application is a continuation in part of my application Serial No. 589,885, filed January 30, 1932.

The machine of the preferred embodiment shown in the accompanying drawings comprises a central motor-and-bit assembly of the oscillating type, a set of planetary or "out-rigger" motor-and-bit assemblies which are compelled to oscillate as a unit with the motor-casing of the central assembly while the out-rigger bits are oscillated on their individual axes by their respective motors, and an inertia member having a lost-motion connection with the shaft of the central bit and through the central-motor shell, with the out-rigger assembly so that reaction of the motive fluid of the central motor will be sustained in part by the inertia member if in the relative oscillation of the central assembly and the out-rigger assembly the oscillation of either becomes too great in amplitude at the expense of the other's corresponding reduction of amplitude, the inertia member thus compelling a proper amplitude of oscillation for both assemblies.

Of the accompanying drawings:

Fig. 1 is a cross-section of the formation at the position of a hole being drilled, showing in side elevation apparatus embodying my invention in its preferred form.

Fig. 2 is a cross-section on line 2—2 of Fig. 4.

Fig. 3 is a bottom plan view of the apparatus.

Fig. 4 is a section of parts of the apparatus showing in elevation the motor-and-bit assembly in expended condition.

Fig. 5 is a similar view showing the motor-and-bit assembly in retracted condition.

Fig. 21 is a section on line 21—21 of Fig. 17.

Fig. 22 is a section on line 22—22 of Fig. 17.

Referring to the drawings, 1 designates a central barrel or casing having therein a central shaft 210 on the lower end of which is mounted a central cutting bit or boring tool 2, the casing 30 and shaft being parts of a fluid pressure motor adapted to effect oscillation of the bit 2 with relation to the barrel 1.

For illustrative purposes I have shown, for the driving of this central bit, a motor of the type 35 illustrated in my prior and copending application Serial No. 271,923, filed April 21, 1928.

In the preferred form of the device, the action of the motor contained in the barrel 1 will effect movement of the central bit with relation to 40 said barrel, preferably an oscillatory movement. The description of the motor in the barrel 1 will be set forth hereinafter, after a description of the motors for the planetary barrels.

Circumferentially arranged with respect to the barrel 1 is a plurality of barrels 11, within each of which is located a fluid pressure motor, such for example as the type illustrated in my prior application Serial No. 534,832, adapted to operate 50 a cutting bit 61. Fixed in each barrel 11 by a screw 5 is a plug 6, (Fig. 17) and also fixed to each barrel 11 by a screw 7 is a plug 8 spaced a predetermined distance below the plug 6. A shaft 210 is rotatably mounted in the plugs or 55.

blocks 6 and 8, and has associated therewith an impeller or vane 111, this impeller being preferably formed integral with the shaft 10. The plugs 6 and 8 are cut away on their top and bottom faces, respectively, and seated in said cut-away portions are the flanges 12 (Figs. 19, 21 and 22) of members 13 and 14, screws 15 securing said flanges 12 to the plugs 6 and 8 respectively.

The plugs 6 and 8, barrel 11, and the members 10 13 and 14 define a chamber 16 within which the impeller 111 may oscillate.

The member 13 is provided with an inlet port 17 and with an exhaust port 18 communicating with the chamber 16, and the member 14 is provided with an inlet port 19 and an exhaust port 20 likewise communicating with the chamber 16 (Fig. 19). The members 13 and 14 are covered, throughout the major portion of their exposed surfaces with rubber coatings secured thereto, and these rubber coatings form seats 21 on the inlet port 17, 22 on the exhaust port 18, 23 on the inlet port 19, and 24 on the exhaust port 20. It will be noted that the pair of seats 21 and 22 and the pair of seats 23 and 24 are approximately in parallel planes.

The shaft 10 and impeller 111 are also coated with rubber, as clearly indicated at 25 in Figs. 14, 15 and 17, lips 26, 26 (Figs. 14 and 15) being formed in the rubber coating on the impeller and bearing against the wall of the chamber 16 to effect a tight joint.

Fixed to the plug 6 by a pin 27 is a collar 28, said collar surrounding the shaft 10 and being provided with a recess or cut-away portion 29 to permit the fluid conducted through the interior 9 of the working barrel 11 to flow around the upper end of the shaft 10 and down around said shaft to constitute a lubricant.

Each of the plugs 6 and 8 is cut away as indicated at 30 to permit uninterrupted passage of the fluid through all of the ports 17, 18, 19 and 20.

Each of the members 13 and 14 is provided with a recess 31, and in these recesses is seated the hub 32 of a double-wing valve 33, this valve having a pivot pin 34 therethrough adjacent to the lower part of the hub 32. The pivot 34 is provided with a knife edge 35 on its upper surface, said knife edge being engaged by a bushing 36 with the same held to the members 13 and 14 by pins 37, and in 50 a bushing 38 which is likewise held against rotation in the members 13 and 14 by a pin 39.

The wings of the valve 33 extend above and below the pivot 34, and are provided with a face 40 adapted to seat against the port seat 21, a face 41 adapted to seat against the port seat 23, a face 42 adapted to seat against the port seat 22, and with a face 43 adapted to seat against the port seat 24. The valve 33 is so constructed and arranged as to close an alternate inlet and exhaust 60 port simultaneously, as for example the inlet port 17 and outlet port 20, with the valve in the position illustrated in Fig. 19.

Assuming that the valve 33 is in the position illustrated in Fig. 19, it will be apparent that fluid 65 being forced through the interior 9 of the barrel 11 will pass through the inlet port 19 into the chamber 16, bearing against and forcing the impeller 111 in a clockwise direction, toward the position illustrated in dotted lines at 44 in Fig. 14. This will effect an exhaust or discharge of the fluid on the opposite side of the impeller 111 out through the exhaust port 18, whence it will 70 continue downwardly through the barrel and to the bit, as will be more fully described hereafter.

75 This movement of the impeller 111 will effect a

rotative movement of the shaft 10, and of the clutch block 45 (Figs. 17 and 18) which is keyed thereto by a key 46, a set screw 47 being utilized as an additional securing element. The block 45 is recessed on each side, as illustrated at 48 in Fig. 18, and projecting upwardly into the recesses 48 are reduced extensions 49, 49 of a sleeve 50, said sleeve 50 being provided with apertures 51 to permit the passage of fluid to the interior of said sleeve, said sleeve also being provided with a spider 52 in which is seated the lower reduced end of the shaft 10, the shaft 10 being threaded at 53 and lock nuts 54 preventing longitudinal displacement of the block 45, the lower nut 54 being pinned at 55.

The sleeve 50 is also provided with a plurality of radially projecting flanges 56, said flanges interengaging recesses 57 in a split bushing 58, the sleeve and its flanges being provided with a rubber coating as clearly illustrated. The split bushing 20 58 is confined between two threaded plugs 59 and 60 threaded into the lower end of the bottom section of the barrel. Secured to the bottom of the sleeve 50 is a bit or cutting tool 61, which may be of any desired size or shape, so long as it is provided with cutting edges 62 adapted to cut with equal efficiency in either direction of oscillation of the bit 61.

All of the rubber surfaces herein described, on rotating or oscillating parts, are provided with 30 grooves 63 to permit the passage of fluid there-around, for lubricating purposes.

It is necessary to provide means automatically operable to unseat the valve 33 from the ports 17 and 20, and move said valve to cover the ports 18 35 and 19, in order that fluid may then enter the chamber 16 by means of the port 17 and move the impeller 111 in a counter-clockwise direction, as for example to the position illustrated at 64 in dotted lines in Fig. 14, forcing the fluid which 40 entered the chamber 16 through the port 19 outwardly through the port 20.

As the preferred form for accomplishing the unseating of the valve 33, for example from the ports 17 or 20, I secure to the upper end of the 45 shaft 10 a collar 65, this collar being keyed to the shaft 10 by a key 66 and held against longitudinal displacement by lock nuts 67, the upper lock nut being pinned to the shaft 10 as at 68. The collar 65 is provided with a pair of radially projecting 50 knocker arms 69, 69. It will thus be appreciated that the knocker arms 69 will be moved in unison with the shaft 10 and impeller 111.

Therefore, as the impeller 111 moves toward the position 44 of Fig. 14, one of the knocker arms 55 69 will also be moved toward engagement with the upper end of the valve 33, as will be readily understood. Continued movement of the knocker arm 69 will result in the pivoting of the valve 33 60 on its pivot 34, and an unseating of the valve 33 from the cooperating seats on the ports 17 and 20. The impact and continued movement of the knocker arm 69, preferably in conjunction with additional means hereinafter described, swings the valve 33 to its opposite position, that is, with 65 the face 41 engaging the seat 23 and with the face 42 engaging the seat 22, thus closing the ports 19 and 18, and permitting the fluid to enter the chamber 16 by means of the port 17 and to be discharged therefrom, by the movement of the 70 impeller 111, through the port 20. As the impeller is moving in the reverse direction, the knocker arms 69 will likewise be moved in reverse direction, until the second knocker arm engages the upper end of the valve 33 and re- 75

peats the operation above described, but in a reverse direction, and this movement will continue, opening and closing alternate inlet and exhaust ports, as long as fluid under pressure is introduced into the barrel.

In order to insure shifting of the valve 33 from one set of inlet and exhaust ports to the opposite set of inlet and exhaust ports, and to prevent any stoppage of the valve 33 on dead center, I provide means to cooperate with and assist the knocker arms 69. This mechanism comprises a socket member 70 located in the bottom of a recess 71 in the clutch block 45, and seated in said socket member is the lower end of a post 72, the upper end of said post being formed with a socket member 73 in which seats the ball end 74 of a pin 75, this pin 75 having a shoulder or collar 76 formed thereon.

Slidable over the pin 75 is a sleeved member 77 which I will hereinafter refer to as a spring arrow. The arrow 77 has a shoulder or collar 78 formed thereon, the collars 76 and 78 forming abutments for a coiled spring 79. A ball end 80 is formed on the upper end of the arrow 77 and seats in a socket member 81 carried by the post 82 which is rockable in a recess 83 formed in the flared end 84 of the valve 33.

Assuming that the motor is in the position illustrated in Fig. 19, with the valve 33 closing the ports 17 and 20. The fluid under pressure as it passes through the interior 9 of the barrel 11 will therefore enter the chamber 16 through the port 19, and will force the impeller 111 in a clockwise direction, exhausting the fluid in the chamber 16 through the outlet port 18. This movement of the impeller will likewise effect a rotation of the shaft 10 and knocker arms 69. The clutch block 45 will also be rotated with the shaft 10, carrying the socket member in a clockwise direction, or the left, as illustrated in Fig. 19, carrying the post 72 therewith. As the rotative movement of the clutch block 45 is continued, the elements 82, 77, 75 and 72 will become straightened, as a toggle, compressing the spring 79 between the collars 76 and 78.

After the aforementioned members have passed their vertical position, the spring 79 will expand, but still be held in compression. As the recess 71 reaches the extent of its stroke to the left, one knocker arm 69 is in engagement with the upper end of the valve 33. Meanwhile the spring 79 through the medium of the arrow 77 and post 82 is exerting a pressure on the lower end of the valve 33, tending to unseat said valve. However, the pressure of the spring 79 is insufficient in and of itself to accomplish this unseating of the valve 33 against the differential force of the fluid against the valve which is incident to the difference in the lengths of the two arms of the valve.

As the knocker arm 69 continues to the left, Fig. 19, it will strike the upper end of the valve 33 and unseat the same. The fluid pressure on the opposite sides of the valve now being equalized, the spring arrow 77 will shoot away from the member 75, instantly pivoting the valve 33 on its pivot 34 and seating the same against the seats of the ports 19 and 18, and directing the fluid through the inlet port 17. Thereupon the fluid will enter the chamber 16 and effect a reverse movement of the impeller 111, and this action will be repeated as long as fluid under pressure is introduced through the barrel 11.

It will be understood and appreciated that as the impeller 111 is oscillating within its chamber 16, the shaft 10 and clutch block 45 are likewise

oscillating, in turn transmitting this oscillation to the sleeve 50 and bit 61 carried thereby.

The torque developed by this motor is directly proportional to the exposed area of the impeller 111, and this torque may be varied by varying the length of the impeller, as well of course as by varying the diameter of the chamber 16.

It will be apparent, from a glance at Fig. 19, that the inlet ports 17 and 19 are located a greater distance from the pivot 34 than are the exhaust ports 18 and 20. This provides an increased leverage on the surfaces of the upper arm of the valve 33, which cooperates with the ports 18 and 20, and overcomes any tendency of fluid introduced into one side of the chamber 16 to unseat the valve from the exhaust port on the same side of said chamber.

Each of the barrels 11 is provided with upper brackets 113 and lower brackets 114, connected to the respective upper and lower brackets 115 and 116 by links 117 and 118 which are pivoted at 119 and 120 respectively. A flexible fluid conducting hose 121 extends to each of the barrels 11, the opposite end of each of these hoses communicating with a chamber 122 formed in a bell 123.

The upper end portion of the barrel 1 is of relatively large diameter and surrounds and has limited rotation about a shoulder portion of an inertia barrel 85, being swiveled thereto by a plug 30 35 threaded into the upper end of said barrel 1 and resting on an antifriction bearing 87, which in turn is mounted on a shoulder 88 formed on said inertia barrel, relative rotative movement of the barrel 1 and the inertia barrel 85 being 35 limited by a pin 1a (Figs. 5 and 13) projecting from the upper end of the barrel 1 and extending into a slot 85a formed in the lower face of an annular shoulder formed on the lower end portion of the inertia barrel 85.

Similarly, the central shaft 210 of the central bit 2 has oscillatory lost-motion connection with a reduced lower end portion 85x of the inertia barrel 85 by reason of a pin 210a (Figs. 6c and 12) projecting horizontally from a collar 210b secured 45 upon the upper end of the shaft, the said pin extending into a lost-motion recess 85b formed in the lower end of the inertia barrel.

A suitable fluid conducting hose 170 (Figs. 4 and 5) is connected to the top of the inertia barrel 85, said hose 170 being connected, at the ground surface, to a suitable pump to force fluid under pressure through the hose. The barrel 85 and hose 170 are supported by cables 89 fixed in eyes on a collar 90, and the bell 123 is supported by 55 cables 91 fixed in eyes in a collar 92, said collar 92 having a plug 93 threaded therein and the bell 123 having a plug 94 threaded thereon, these plugs overlapping and having an anti-friction bearing 95 interposed therebetween for free rotation of said bell.

The inertia barrel 85 is provided with ports 124 (Fig. 5) so that fluid under pressure passing through the hose 170 and inertia barrel 85 will also be distributed under the same pressure 65 through the ports 124, chamber 122, and thence through the hoses 121 to each of the barrels 11 and the fluid pressure motors contained therein. It will be obvious that a portion of the fluid conducted through the hose 170 will be introduced 70 directly through the main lead 171 into the barrel 1 and to the fluid pressure motor contained therein.

The upper ends of the hoses 121 are fixed in a plug 125 threaded into the lower end of the bell 1.

123. The bell 123 is provided with a plurality of brackets 126 having eyes 127, and a supporting cable 128 passes through each of the eyes 127 to rings or the like 129 fixed to each head 130 on 5 the barrels 11.

It will thus be apparent that each of the individual barrels 11 is independently and flexibly supported from and connected to the bell 123. The upper end of the bell 123 is reduced in diameter, 10 as illustrated at 131, and is slideable over the inertia barrel 85. The lower end of the inertia barrel 85 is provided with ports 171^a communicating with the main passage 171 in the inertia barrel and with the hollow interior of the barrel 1 and 15 with the fluid motor carried thereby.

The cables 89 preferably meet at a point above the collar 90, and extend upwardly as a single cable for ease of handling at the ground surface, and the same is true of the cables 91, independent 20 operating means for these cables being provided at the ground surfaces.

The barrel 1 is provided with arms 139 and 140, and each of the barrels 11 is provided with arms 141 and 142, these arms cooperating with 25 the links 117 and 118 respectively, as clearly illustrated in Fig. 4, to limit expansion of the barrels 11 relative to the barrel 1, as will be hereinafter more fully explained.

Each of the bits 2 and 61 is provided with fluid 30 conducting passages 143 closely adjacent to the cutting edges thereof, through which apertures 143 the fluid is forced after operating the motors in the barrels 1 and 11. This fluid effects a cooling action on the bits 2 and 61, and furthermore 35 flushes the cuttings of said bits out of the bore 144 drilled by said bits. Said fluid is, of course, forced upwardly through the bore 144, whence it passes to the usual slush pit, where the muddy fluid is allowed to settle and is again re-pumped 40 through the hose 170.

The bits 61 are located on a plane above the plane of the bit 2 and are so arranged that even in their expanded position their cutting area will 45 overlap the cutting area of the bit 2, thus insuring complete drilling of the bore or shaft 144.

In Fig. 4 the device is illustrated in expanded position, and in Fig. 5 the device is illustrated in contracted or collapsed position, this contraction being effected by raising the cable 89, which will 50 draw the inertia barrel 85 upwardly, and, through the medium of the flange 88 and plug 86 will raise the barrel 1 upwardly until the upper end thereof contacts with the plug 125 in the bell 123.

This raising of the barrel 1 will also raise the 55 brackets 115 and 116, drawing the barrels 11 inwardly toward the barrel 1 through the medium of the links 117 and 118.

When the cables 89 are lowered, the barrel 1 will drop, and, through the medium of the links 60 117 and 118 will force the barrels 11 outwardly with respect to said barrel 1, until the arms 139 and 140 and 141 and 142 have engaged the upper and lower edges of the links 117 and 118 respectively, as clearly illustrated in Fig. 4, thus preventing further expansion or outward movement 65 of the barrels 11 relative to the barrel 1.

Because of the expandable and contractile or collapsible feature of my novel assembly, I am enabled to case a shaft as it is bored, as clearly 70 illustrated in the drawings, wherein the casing sections 145 are lowered or driven into the bore in any suitable manner, as by means of the hydraulic jacks 146 and ram 147, a driving shoe 148 being fixed to the lowermost section 145.

75 These sections 145 are united in any suitable

manner, as by bands 149 on the exterior thereof, and each section 145 is preferably constructed of segments 150 united, on their interior, by the straps 151 which may be welded or riveted there-to, or in any other desired manner. Each section 5 145 preferably is provided with an outlet opening 145^a so that the drilling fluid can flow therefrom to the slush pit although additional sections have been assembled or are being assembled above the opening 145^a through which the drilling fluid at 10 the moment is being discharged, so that discontinuance of the drilling operation is not necessary for the addition of casing sections.

In order to provide for a sufficiently high amplitude of oscillation of the central bit 2 to provide cutting of the bit throughout the full circle without a large number of blades on the bit, and sufficiently large amplitude of oscillation for the planetary or "out-rigger" assembly to provide cutting of the out-rigger bits throughout the full 20 circle about the central bit without a large number of out-rigger bits, I preferably employ for the central motor a motor of the type illustrated in my copending application Serial No. 271,923, filed April 21, 1928. 25

As is shown in Figs. 5 and 6^c the lower portion of the inertia member 85 is of relatively small diameter and extends into the upper portion of the central motor casing 1, its axial motive-fluid bore 171 communicating with the interior of the 30 casing through ports 171^a, 171^b (Fig. 6^c) and its exterior being rotatably sealed to the top of a belt (Fig. 5) formed on the upper end of the casing.

Mounted in the casing and surrounding and rotatably sealed to the shaft 210 is a grease container 201 (Figs. 6^b and 6^c) containing an annular piston 202 (Fig. 6^c) adapted to bear down upon a body of grease in the container, under the force of high-pressure drilling fluid entering 40 the top of the container through apertures 203, 203 in its walls (Fig. 6^c), the portion of the container under the piston being in communication, through inlet apertures 204, 204, an axial bore 205, and outlet apertures 206, 206 in the shaft 45 210, with the interior of a hollow-bit driving piston hereinafter to be described. The container is provided with an inlet 207 (Fig. 6^b) closed by a removable plug 208 for replenishment of the grease. 50

Fixed in the casing 1, below the grease container 201 and below a slide member 209 is an inner casing or cylinder 218, having vertical inlet channels 219, and vertical discharge or exhaust channels 220, Fig. 11. The inlet channels 55 219 have upper and lower inlet ports 221 and 222 respectively leading to the interior of the inner casing 218, and the discharge or exhaust channels 220 have the upper and lower discharge ports 223 and 224 respectively, leading from the 60 interior of the casing 218. The upper ends of the inlet channels 219 are open, as clearly illustrated in Fig. 11, but their lower ends are closed, and the lower ends of the discharge channels 220 are open but their upper ends are closed. 65

Slidably fitted within the cylinder 218 are the valves or sleeves 225 and 226 of spider form projecting from which are radial pins 227 and 228 respectively (Fig. 8) which work or slide in the vertical bearings 229 and 230 respectively. The pins 227 and 228 are connected by valve connecting rods 231 which work in the rod bearings 232 in the cylinder wall in order that the valves 225 and 226 will be compelled to move in unison. The ports 221 and 224 (Figs. 8 and 11) are so dis- 75

posed and arranged that when one series of inlet ports are opened by their valve the series of discharge or exhaust ports at the same end of the cylinder will be closed by the said valve, and the 5 reverse will be true of the corresponding series of inlet and discharge ports at the opposite end of the cylinder. Also, when one series of discharge ports are opened by their valve the inlet ports at the same end of the cylinder will be 10 closed and the reverse will be true of the inlet and discharge ports at the other end of the cylinder. The upper and lower ends of the cylinder 218 have the respective plugs 233 and 234 threaded therein or otherwise attached thereto. The 15 valve 225 has valve extensions or prongs 235 extending downwardly therefrom and the valve 226 has similar valve extensions or prongs 236 extending upwardly therefrom.

Splined within the cylinder 218 between said 20 valves is a hollow piston 238 having a liner 239 therein and provided with the end stuffing boxes 240 and 241 forming bearings on the shaft 210.

The splining of the piston in the inner casing is effected by keys 257, 257 secured in the inner 25 casing 218 and extended into vertical keyways 258, 258 (Fig. 6b) in the piston 238. The piston 238 is adapted in being vertically reciprocated to impart oscillations to the shaft 210, cam rollers 244, 244 running in helical cam grooves 243, 243 30 being mounted on the ends of a pin 245 which extends transversely through and projects from the shaft 210 and is fixed therein.

The above mentioned slide member 209 (Figs. 6b, 7 and 8) is secured to the upper ends of the 35 rods 231 by screws 209a, 209a so that it is compelled to move up and down with the valves 225, 226, and it is formed with a spider portion 209b defining passages 259, 259 for the motive fluid and with a slot 260 adapted at the end of the up 40 stroke and at the end of the down stroke of the piston 238 to be at the position at which a roller 261 arrives at that time in the rotation of the shaft 210, so that during the down stroke of the piston the valve assembly including the slide member 209 is held in its elevated position by contact of the cam roller 261 running on the underside of the spider member 209b, as shown in 45 Figs. 6b and 8, against the force of a helical compression spring 262 surrounding the shaft 210 and interposed between the piston and the lower valve 226 so as to urge the entire valve assembly downward, the cam roller 261 arriving at the slot 260 in the spider member 209b at the instant that the piston reaches the contact lugs 236 on the 50 lower valve to initiate the movement of the valve, said spring then impelling the entire valve assembly quickly to its lowermost position and thereby reversing the valve arrangement for the return or up stroke of the piston, during which 55 stroke the same roller 261 runs on the upper face of the spider portion 209b of the slide member 209, again registering with the slot 260 at the end of the up stroke of the piston and thus permitting the entire valve assembly to be elevated to its uppermost position by a helical compression spring 263 (Fig. 6b) which surrounds the shaft 210 and is interposed between the piston and the spider portion of the upper valve member 225, the piston engaging the contact lugs 235 of the upper 60 valve member to initiate the upward movement of the valve assembly, the valve arrangement thus being reversed for the next downward stroke of the piston.

In the operation of the apparatus the motive 75 fluid forced downward through the hose 170 in

part passes through the central casing 1 to operate the motor therein for relative oscillation of the shaft 210 and the casing 1, the motive fluid passing from the casing 1 through the central bit 2 to wash the cuttings to the top of the well. Part of the motive fluid passes from the inertia member 85 through the channels 124 and hose conduits 121 (Fig. 5) and actuates the motors contained in the out-rigger casings 11 to effect relative oscillation between the said casings and 10 their respective out-rigger bits 61, the casings 11 being held by the link members 118 against oscillation about their own axes but being compelled by said links to oscillate as a unit with the central casing 1. 15

The shaft 210 is mounted in bearings in the plugs 233 and 234, and extends beneath the latter, said extended end being connected, by nut 246 and washer 247 (Fig. 6a) to the chuck or drill collar 248. The upper end of this chuck within 20 the casing 1 is provided with inlet ports 249, and said chuck works between the bearing rings 250 and 251 and has an annular rib 252 which runs between the bearings 253 and 254, retained by said bearing rings, said rings being threaded into the 25 lower end of the casing 1, as clearly illustrated in Fig. 6a. The bit 2 is connected to the lower end of this chuck 248 in any desired manner, as by means of a tapered key 2a (Figs. 6a and 10.) This bit has channels 256 extending therethrough. 30 Any suitable type of drill, bit or boring tool may be employed, the type depending on the character of the formation being drilled, but is constructed and arranged to effect an equal cutting action in either direction of oscillation. 35

If a shaft is being drilled or bored with my device, and the casing is following the drills in their descent, should it be desired to withdraw the machine for any purpose, raising the cables 89 will effect a contraction of the assembly until 40 the greatest diameter of said assembly is less than the internal diameter of the casing 145, permitting withdrawal of the entire assembly upwardly through the casing. On replacing the device, it is lowered into the casing until the bits 2 and 61 are below the shoe 148, whereupon the 45 lifting strain on the cables 89 is relieved, and the device will automatically assume its expanded position, as illustrated in Fig. 2. The expansion of the planetary bits relative to the central bit 50 may be halted at any suitable point, so that shafts or bores of varying diameters throughout their lengths may be drilled with a single machine.

Furthermore, by the use of my device, it is not 55 necessary to drill a successively decreasing size of shaft, as has been heretofore necessary, the contractile feature of my device permitting the casing of the shaft with one diameter of casing to any desired depth.

The planetary fluid motors and their assemblies constitute a primary reaction and inertia structure such that as rotation is imparted to the bit 2, rotation in an opposite direction will be imparted to the barrel 1 and the assembly of bits 61, which are secured against rotation with relation to the barrel 1 by the connecting links 118. If either the outrigger bit assembly or the central bit excessively resists rotation about the common center, the other will rotate faster and 60 farther than in normal operation until the projection 1a is stopped by the end wall of the lost-motion slot 85a, (Figs. 5 and 13) or until the projection 210a is stopped by the end wall of the lost-motion slot 85b (Figs. 6c and 12), whereupon the 70 75

relatively free rotation of such member or structure will be resisted by the inertia of the barrel 85, which will compel rotation of the previously retarded member or structure.

5 Thus, while each of the bits 61 is rotating about its own axis, said bits 61, as a part of the inertia assembly, will be moved in an orbital path in the opposite direction about the bit 2, while rotating on their own axes, insuring complete and thorough drilling or boring of the entire shaft as the machine descends.

10 My novel machine will drill any size of shaft varying in diameter from the extreme contracted or collapsed position to the extreme expanded position.

15 It will be appreciated and understood that the number of bits 61 shown herein is for illustrative purposes only and that I am not confined to any particular number, but may utilize any number 20 of bits required or desired.

20 When the load is released from the cables 89 to permit dropping of the barrel 1, it will be appreciated that the load is then taken up by the cables 91, each set of cables being of sufficient strength to support the entire assembly.

25 After a shaft is drilled according to my invention, the drilling machine is removed and the shaft is then pumped out in any desired manner, and lateral tunnels can be bored at any desired 30 depths or levels.

30 Modifications are possible within the scope of my invention as defined in the appended claims.

I claim:

35 1. Earth boring apparatus comprising an oscillating central bit, an oscillating planetary bit, and means for oscillating each of the said bits on its own axis and for oscillating the planetary bit about the central bit.

40 2. Earth boring apparatus comprising an oscillating central bit, a motor of the oscillating type for driving said bit, bit-driving means so connected to an element of the said motor as to be oscillated about the axis of the central bit by the reaction force of the said motor, and bit 45 means mounted on said bit-driving means.

45 3. Earth boring apparatus comprising a central bit, a motor of the oscillating type for driving said bit, bit-driving means so connected to an element of the said motor as to be oscillated about the axis of the central bit by the reaction force of the said motor, bit means mounted on said 50 bit-driving means, and means for oscillating the said bit means about an axis other than that of the central bit.

55 4. Earth boring apparatus comprising a central bit, a motor of the oscillating type for driving said bit, bit-driving means so connected to an element of the said motor as to be oscillated about the axis of the central bit by the reaction force of the said motor, bit means mounted on said bit-driving 60 means, and an inertia member having lost-motion connection to each of two relatively oscillating elements of the said motor for compelling each of the said elements to oscillate with relation to the formation being bored.

65 5. Earth boring apparatus comprising a central bit, a set of planetary bits arranged about said central bit, and means for oscillating each of said bits on its own axis and for oscillating the planetary bits about the axis of the central bit.

70 6. Earth boring apparatus comprising a rotative central bit, a rotative planetary bit, and means for driving each of the said bits on its own axis and for driving the planetary bit about the central bit, said means comprising a pressure fluid

motor adapted to discharge the motive fluid adjacent the bits for washing the cuttings to the top of the ground, the planetary bit being journaled on the motor casing assembly so as to be constrained to rotate therewith about the axis of the central bit, and the axes of the two bits being substantially parallel.

7. Earth boring apparatus comprising a central bit, a pressure fluid motor of the oscillating type for driving said bit, the motor being adapted 10 to discharge the motive fluid adjacent the bit, bit-driving means so connected to an element of the said motor as to sustain the reaction force of the motor, and bit means on said bit-driving means.

15 8. Earth boring apparatus comprising a central bit, a pressure fluid motor of the oscillating type for driving said bit, bit driving means so connected to an element of said motor as to sustain the reaction force thereof, a planetary bit 20 mounted on said bit-driving means, a pressure fluid motor for driving said planetary bit on its own axis, and a conduit common to the two motors for supplying them with motive fluid.

9. Earth boring apparatus comprising a central 25 bit, a pressure fluid motor of the oscillating type for driving said bit, bit driving means so connected to an element of said motor as to sustain the reaction force thereof, a planetary bit mounted on said bit-driving means, a pressure fluid motor 30 for driving said planetary bit on its own axis, a conduit common to the two motors for supplying them with motive fluid, and an inertia member having lost-motion connection to each of two relatively oscillating elements of the motor of 35 the central bit for compelling each of the said elements to oscillate with relation to the formation being drilled.

10. In a well drilling machine of the kind described, a central bit, a plurality of bits circumferentially arranged with respect to said central bit, means to effect movement of each of said bits about its axis, means to simultaneously effect movement of said circumferentially arranged bits in an orbit about said central bit, and means to 45 expand and contract said circumferentially arranged bits with respect to said central bit.

11. In a well drilling machine of the kind described, a central bit, a plurality of bits circumferentially arranged with respect to said central 50 bit, means to effect movement of each of said bits about its axis, means to simultaneously effect movement of said circumferentially arranged bits in an orbit about said central bit, means to expand and contract said circumferentially arranged bits with respect to said central bit, and means to limit the expansion and contraction of said circumferentially arranged bits.

12. In a well drilling machine of the kind described, a central barrel, a bit carried thereby, 60 means to effect movement of said barrel and bit about its axis, a plurality of barrels circumferentially arranged with respect to said central barrel, a bit carried by each of said outer barrels, means to effect movement of each of said outer 65 bits about its axis, means including a plurality of pivoted links inter-connecting said central barrel and said outer barrels to effect revolution of said outer bits about said central bit simultaneously with the axial movement thereof, and 70 means to move said central barrel longitudinally with respect to said outer barrels.

13. In a well drilling machine of the kind described, a central barrel, a bit carried thereby, means to effect movement of said barrel and bit 75

about its axis, a plurality of barrels circumferentially arranged with respect to said central barrel, a bit carried by each of said outer barrels, means to effect movement of each of said outer bits about its axis, means including a plurality of pivoted links inter-connecting said central barrel and said outer barrels to effect revolution of said outer bits about said central bit simultaneously with the axial movement thereof, and means to move said central barrel longitudinally with respect to said outer barrels, longitudinal movement of said central barrel actuating said links to draw said outer barrels toward said central bit or push said outer barrels away from said central barrel.

14. In a well drilling machine of the kind described, a central barrel, a bit carried thereby, means to effect movement of said barrel and bit about its axis, a plurality of barrels circumferentially arranged with respect to said central barrel, a bit carried by each of said outer barrels, means to effect movement of each of said outer bits about its axis, means including a plurality of pivoted links inter-connecting said central barrel and said outer barrels to effect revolution of said outer bits about said central bit simultaneously with the axial movement thereof, means to move said central barrel longitudinally with respect to said outer barrels, longitudinal movement of said central barrel actuating said links to draw said outer barrels toward said central bit or push said outer barrels away from said central barrel,

15. In a well drilling machine of the kind described, a central barrel, a bit carried thereby, means to effect movement of said barrel and bit about its axis, a plurality of barrels circumfer-

tially arranged with respect to said central barrel, a bit carried by each of said outer barrels, means to effect movement of each of said outer bits about its axis, means including a plurality of pivoted links inter-connecting said central barrel and said outer barrels to effect revolution of said outer bits about said central bit simultaneously with the axial movement thereof, means to move said central barrel longitudinally with respect to said outer barrels, longitudinal movement of said central barrel actuating said links to draw said outer barrels toward said central bit or push said outer barrels away from said central barrel, and means adapted to engage said pivoted links to limit the movement of said outer barrels from said central barrel.

16. In a well drilling machine of the kind described, a central barrel, a bit carried thereby, means to effect movement of said barrel and bit about its axis, a plurality of barrels circumferentially arranged with respect to said central barrel, a bit carried by each of said outer barrels, means to effect movement of each of said outer bits about its axis, means including a plurality of pivoted links inter-connecting said central barrel and said outer barrels to effect revolution of said outer bits about said central bit simultaneously with the axial movement thereof, means to move said central barrel longitudinally with respect to said outer barrels, longitudinal movement of said central barrel actuating said links to draw said outer barrels toward said central bit or push said outer barrels away from said central barrel, and stop arms carried by said central barrel and said outer barrels adapted to engage the pivoted links to limit movement of said outer barrels from said central barrel.

CLYDE E. BANNISTER.
